EVAPORATING APPARATUS

Curt Fredrik Rosenblad, Stockholm, Sweden, assignor to Aktiebolaget Rosenblads Patent, Stockholm, Sweden, a corporation of Sweden

Application August 14, 1940, Serial No. 352,551
In Sweden June 17, 1939

7 Claims. (Cl. 159—13)

The present invention relates to evaporating apparatus, and more particularly to such apparatus of the surface heating type with vertically arranged heating tubes for evaporating liquid distributed in film formation, outer surfaces of heating tubes being exposed to a heating medium, while the inner surfaces receive liquid to be evaporated delivered at the upper ends of the tubes.

It is the general object of the invention to improve apparatus of the above type and to render it more effective. With this in view the invention is concerned with the improvement of various elements and arrangements in such apparatus. However, each feature of novelty here disclosed is applicable independently of the others and alone under certain circumstances may give satisfaction. In some cases though it may be desirable or necessary to combine all or certain features of the invention in the same apparatus.

One object of the invention is to provide each heating tube with perfect liquid distributing means at the upper end of the tube for passing the liquid on to the inside tubular surfaces so as to form thereon a relatively thin and uniform liquid film. Preferably this means comprises a nozzle like inlet device of a special design for each of the heating tubes which devices are fitted to the upper ends of the tubes and suited to deliver the liquid in the proper manner while giving it a whirling motion in order to increase the efficiency. The inlet devices according to the invention also have the advantage that the inlet passages thereof may have a relatively large cross-sectional area throughout, whereby there is little danger that they shall be obstructed by deposits of any kind.

Another object is to provide means for preventing evaporation within said inlet devices or at the adjacent zone of the inside tubular surfaces. This is important in order to prevent deposit of scale, which might cause serious disturbances in the supply of liquid.

Still another object of the invention is to provide the heating tubes with discharge means at the lower ends of the tubes for permitting the escape of both the liquid and vapor generated therefrom, from the tube passages into a space below, in such a manner that no mingling occurs between the liquid and the vapor. This makes it possible to have the liquid and vapor flow in the same direction within the tube passages so that the velocity of the liquid is accelerated by the flow of vapor, which improves the efficiency. But moreover, at the same time

separation of the vapor from the liquid is made so complete at the exit from the tubes passage that additional means for that purpose may be dispensed with in contrast to earlier practice.

5 Further objects and aspects of the invention will be apparent from the following specification describing more in detail an apparatus comprising the various improvements, as illustrated by way of example in the accompanying drawings.
10 In the drawings Fig. 1 shows in vertical section an apparatus with the various inventive features combined; Fig. 2 shows in vertical section, on an enlarged scale, the upper end of a heating tube with an inlet device according to the invention; Fig. 3 is a top view, with a cover plate removed, of the inlet device shown in Fig. 2; Fig. 4 is a cross-sectional view taken on the line IV—IV of Fig. 3; Fig. 5 is a top view of a modified inlet device of the same type; Fig. 6 is a cross-sectional view of one embodiment of discharge means for the heating tubes; Fig. 7 is a cross-sectional view taken on the line VII—VII of Fig. 6; Fig. 8 is a side view of another embodiment of similar discharge means; and Fig. 9 is a cross-sectional view taken on the line IX—IX of Fig. 8.

25 Referring now to Fig. 1 of the drawings, the apparatus shown comprises a plurality of heating tubes *1a* and *1b* arranged vertically between horizontal tube plates in a casing which is divided into different compartments by the tube plates. In this case the heating tubes are disposed in two separate groups, an upper group of tubes *1a* between upper and lower tube plates *a'* and *a''*, respectively located above a lower group of tubes *1b* between upper and lower tube plates *b'* and *b''*, respectively, but in other cases there may be more groups or only a single one. Between the tube plates the respective groups of heating tubes extend through heating zones provided 30 by compartments A and B, whereby the exterior surfaces of the heating tubes are exposed to a heating medium supplied to the respective heating chambers through the pipe system 10—10a—10b. Above and below each group of tubes there are defined other compartments in which terminate the adjacent tube ends of the group below or/and above, as the case may be, and the tube ends project somewhat from the tube plates into these compartments. Accordingly, at the top of the apparatus there is an upper compartment *C*₁ above the upper group *1a*, in which terminate the upper ends of these tubes, while another compartment *C*₂ is located between the groups *1a* and *1b*, below the former and above 35 the latter, in which compartment terminates the

lower ends of the tubes of the group 1a and the upper ends of the tubes of the group 1b, and finally the lower ends of group 1b terminate in a lower compartment C₃ below that group at the bottom of the apparatus. In this way the two groups of tubes are connected in series so that the inside tubular surfaces receive liquid delivered at the upper ends of the tubes from the respective compartment C₁ or C₂ located next above. The liquid is first introduced into the uppermost compartment C₁ through the intake 11 to be passed through the tubes of the upper group 1a into the compartment C₂ and therefrom through the tubes of the lower group 1b into the lowermost compartment C₃, while being finally withdrawn from the latter through the outlet opening 12. For distributing the liquid in proper manner to the inside tubular surfaces, the heating tubes are provided with nozzle like inlet devices 2 fitted to the upper ends of the tubes through which the tubes communicate with the respective compartments C₁ or C₂ located next above, on the bottom of which there is maintained a pool of liquid of sufficient depth for the liquid to be delivered by these inlet devices to the tubes. Further, the heating tubes are provided with discharge means 3a or 3b at the lower ends within the respective compartment C₂ or C₃ located next below, which discharge means are designed to provide separate escape of the liquid and vapor generated therefrom, from the tube passages into such a lower compartment so that the liquid will be collected at the bottom of these compartments whereas the vapor will flow into the upper portions thereof. The vapor received in the compartments C₂ and C₃ are removed therefrom in parallel by the pipe system 13a—13b—13.

As shown, the upper group of heating tubes 1a may suitably consist of a greater number of tubes than the lower group 1b and the tubes may be either conical in shape with the cross-sectional area decreasing downwards in the directions of flow, as in the group 1a, or cylindrical as in the group 1b. By using such conical tubes or by the group arrangement disclosed with the number of tubes decreasing through successive groups from an upper group to a lower one in the direction of flow, the total tubular surface receiving the liquid is diminished as the quantity of liquid is diminished by evaporation so that the quantity of the liquid passing per unit of surface is maintained approximately constant throughout the apparatus, and thus a high efficiency is secured.

Another novel feature is that the upper ends of the heating tubes project above the tube plates in the respective compartments to such a height that the portion of the tube to which the liquid liquid is delivered is located within that compartment so that the liquid is delivered at a level above the heating zone of the tubes in order to prevent any evaporation in or adjacent to the inlet devices of the tubes for reasons already stated.

For the same purpose it may be suitable to surround the projecting upper tube end portions with heat insulating material, as indicated by V in the compartments C₂.

If required, further protection against evaporation in the inlet devices 2 may be provided by making these devices of a non-heat conducting material or using such material at least for those surfaces which are contacted by the liquid.

The inlet devices 2 for the heating tubes are

preferably of a nozzle like construction, as more clearly shown in Figs. 2 through 5, and consist of hollow pieces fitted to the upper ends of the tubes in the fashion of a plug. Thus the device has a cylindrical portion introduced into the tube passage in tight contact with the tube wall and has a top portion projecting above the tube end. The top of the inlet device is closed by a removable cover plate 20 and in the projecting top portion there is provided one or more lateral entrance ports 21 directed tangentially into a vertical cylindrical bore 22 in that portion, which bore at the bottom communicates with a conically widening orifice 23 opening from the cylindrical portion downwardly into the tube. The liquid enters through ports 21 into the upper bore 22 with a certain velocity in tangential direction and is caused by the centrifugal forces to be spread in the form of a film over the conical surface defining the orifice 23 from the lower edge of which surface the film passes on to the tube wall to flow down along the same by gravity. Thereby, a very smooth and easily controllable distribution of the liquid to the tube walls as a perfectly uniform film is attained, while furthermore a turbulent flow of the liquid is effected by virtue of the centrifugal action of the device.

In such devices the upper bore 21 and the orifice 23 can either be concentrically disposed, as in Figs. 2 through 4, and in that case the device should have at least two entrance ports 21 at diametrically opposite places in order to obtain a strong centrifugal action, or the bore 22 and the orifice can be eccentric as at 23a in the modification according to Fig. 5, in which case a single entrance port 21 may be sufficient.

Naturally, however, there may also be used other liquid distributing means in combination with the other inventive features.

Returning again to the discharge means 3a and 3b for the heating tubes according to the invention it will be recognized that the different modifications shown are of the same general type, and in actual practice of course only one or the other is used in the same apparatus.

As shown in Figs. 6 and 7, and 8 and 9, respectively, the discharge means 3a or 3b consists of a comparatively short tube piece of equal diameter with the heating tube. This tube piece is removably attached to the heating tubes 1a or 1b at the lower end thereof by means of a suitable connection device X or Y, as a flow conducting tube extension located within the compartment C₂ or C₃ below the heating tube. In the tube piece, the lower end of which is open, there are provided one or more lateral outlet openings 4a or 4b for vapor, these lateral openings having preferably the shape of longitudinal slots. Further, each of the lateral openings 4a or 4b has the periphery, at least the upper non-vertical edge portions thereof, surrounded by a flanges or collar 5a or 5b or the like projecting radially inwards into the tubular passage. These collars 5a or 5b have suitably a streamlined shape viewed in the direction of flow within the tubular passage and serve as guiding surfaces for the liquid flow, so that the film of liquid on the inside tubular surface is broken up at points just above the lateral openings 4a or 4b so that the liquid flow is deflected around the openings. This prevents the liquid from either flowing through the lateral openings 4a or 4b or forming a veil across the same, and consequently the vapor may escape separately through said unrestricted openings, without mingling with the

liquid, whereas the liquid leaves separately at the lower open ends 6a or 6b. Hence the vapor enters the upper portions of the compartments C₂ or C₃ at a higher level than the liquid, which is collected at the bottom of these compartments.

In the embodiment 3a of such discharge means, as shown by Figs. 6 and 7, the tube extensions have a plurality of lateral slot-shaped outlet openings 4a which are located at a distance above the lower end of the extension piece and provided with flanges or collars 5a consisting of inwardly bent material of the tube piece.

In the modification 3b of similar discharge means, as shown by Figs. 8 and 9, the tube extension has only a single lateral outlet opening 4b cutting off a portion of the tube periphery from and including a portion of the lower edge thereof so that there the lateral opening 4b merges into axial lower opening 6b, and in this more simple construction the lateral opening 4b is provided with a flange or collar 5b which need surround only the upper curved or inclined periphery of the opening and which may suitably be welded to the edge thereof.

Of course, it is not necessary that such discharge means should include removable extension pieces although this is the most practical, but it is also possible to make similar tube extensions integral with the heating tubes, by welding, for instance, or instead the heating tubes themselves may have the end portions formed as discharge means.

Further, it is understood that the discharge means for the heating tubes may be changed in various ways not here disclosed and that there may be used entirely different discharge means in connection with the diverse inventive features described above.

In conclusion, it shall be emphasized that the scope of the invention is not limited otherwise than by the appended claims.

What I claim is:

1. In an evaporating apparatus, a vertically arranged heating tube, means for heating the exterior of said tube, liquid distributing means disposed at the upper end of said tube for supplying liquid to be evaporated in a film to the interior surface of the tube, the lower portion of said tube being formed with a lateral opening for the discharge therethrough of vapor, and means within said tube presenting guiding surface for diverting the liquid film away from said opening, whereby the vapor is discharged through said opening without mingling with the liquid.

2. In an evaporating apparatus, a vertically arranged heating tube, means for heating the exterior of said tube, liquid distributing means disposed at the upper end of said tube for supplying liquid to be evaporated in a film to the interior surface of the tube, the lower portion of said tube being formed with a lateral opening for the discharge therethrough of vapor, and a flange extending inwardly from the wall of said tube around at least the upper edges of said opening to divert the liquid film away from the opening, whereby the vapor is discharged through said opening without mingling with the liquid.

3. In an evaporating apparatus, a vertically

arranged heating tube, means for heating the exterior of said tube, liquid distributing means disposed at the upper end of said tube for supplying liquid to be evaporated in a film to the interior surface of the tube, a hollow member 5 removably connected to the lower end of said tube, said member being formed with a lateral opening for the discharge therethrough of vapor, and means within said member presenting guiding surface for diverting the liquid film away from said opening, whereby the vapor is discharged through the opening without mingling with the liquid.

4. In an evaporating apparatus, a vertically arranged heating tube, means for supplying heat to the exterior of said tube, a nozzle member disposed at the upper end of the tube and having a tangentially disposed inlet port, means for supplying liquid to be evaporated to said port, said nozzle having a conical orifice extending into said tube, the smaller end of said orifice communicating with said tangential port and the larger end substantially coinciding with the inner wall of said tube, whereby liquid is spread in a film over the surface of said orifice from where the film flows onto the inner surface of the tube, and means for collecting liquid and vapor discharged from the lower end of said tube.

5. In an evaporating apparatus, a vertically arranged heating tube, means for heating the exterior of said tube, a liquid distributing nozzle extending into and contacting the upper end of said tube and having an orifice for supplying liquid to be evaporated in a film to the interior surface of said tube, at least the portion of said nozzle in which the orifice is formed being made of material having a low coefficient of heat conductivity, and means for collecting liquid and vapor discharged from the lower end of said tube.

6. In an evaporating apparatus, means including a bottom wall forming an inlet chamber for liquid to be evaporated, means for supplying liquid to said chamber, a vertically arranged heating tube extending through said wall, means for heating the exterior of a portion of said tube below said wall, a liquid distributing nozzle located in said chamber and extending into the portion of said tube which is above said wall for supplying a film of liquid to the interior surface of said tube, the liquid in said chamber serving to maintain said nozzle and the upper portion of said tube at a temperature below the boiling point of the liquid, and means for collecting liquid and vapor discharged from the lower end of said tube.

7. In an evaporating apparatus, a vertically arranged heating tube, means for heating the exterior of said tube, a liquid distributing nozzle extending into the upper end of said tube and having an orifice for supplying liquid to be evaporated in a film to the interior surface of said tube, heat insulating material disposed around the upper portion of said tube into which the nozzle extends, and means for collecting liquid and vapor discharged from the lower end of said tube.

CURT FREDRIK ROSENBLAD.
